UNITED STATES PATENT OFFICE

HERBERT JAMES MARTIN, OF ABBOTSFORD, EASTBOURNE, ENGLAND.

WINDOW, DOOR, AND THE LIKE.

977,461.

Specification of Letters Patent.

Patented Dec. 6, 1910.

Application filed February 5, 1910. Serial No. 542,225.

To all whom it may concern:

Be it known that I, HERBERT JAMES MARTIN, a subject of His Majesty the King of England, residing at Abbotsford, Prideaux Road, Eastbourne, Sussex, England, have invented certain new and useful Improvements in Windows, Doors, and the Like, of which the following is a specification.

This invention relates to certain improvements in windows, doors and the like of the kind in which the sashes, frames or the like are hinged together and the free ends of the sashes are adapted to slide along the top and bottom of a single frame, the hinge line being vertical.

In windows, doors or the like of the kind referred to it has already been proposed to provide one free corner of each sash with a pivot pin working in a hole in a double grooved slide, and the other free corner with a slide adapted to engage and slide along a fixed guide and connected to the sash by a vertical hinge pin so as to permit the free ends of the sashes to be moved toward and away from each other.

The fixed guide has been suitably attached to or has formed part of the window frame, and behind the guide a bar has been eccentrically or otherwise pivoted in end brackets and adapted when rotated, or partly rotated, to engage and hold the two hinged slides of the sashes from movement. The rotation of the bar has been effected by one or more handles connected to the bar and the weight of the sashes has been taken by balls or wheels arranged to run on a suitable bearing surface.

An object of the present invention is to enable the frame to be fixed in position and the sashes or the like to be attached later to the frame without in any way disturbing the frame at the time of attaching the sashes, thereby rendering the outlay on the attaching and locking mechanism thereof unnecessary until such time as the sashes are actually required to be attached to the frame, or on the other hand avoiding the necessity of cutting the frame, after this has been fixed in the building, when it is subsequently desired to fit the attaching and locking mechanism. To this end brackets carrying the locking bar are provided and so arranged that they can be merely fitted against the rabbets of the frame. One of these end brackets is formed with a key-hole slot, and a lug or projection is cast or provided on

the bar in such a position, that to insert the pivot ends of the bar, which are of lesser diameter than the bar itself, into the end brackets, the bar must be turned diagonally. When this is done the bar can be moved a sufficient distance through the said key-hole-slotted end bracket to permit the opposite pivot end to be brought exactly opposite the hole in the end bracket corresponding thereto. The bar is then drawn back to enter the last mentioned pivot end into the bracket and allowed to drop square, when the lug will then be at an angle to the slot, and in conjunction with the shoulder at the other end will prevent any lateral movement of the bar. Further the guides for the double grooved slides, in which the pivot pins of the sash corners work, are formed by means of a channel guide, shaped at its open side to engage the oppositely situated grooves of the pivot pin slides. Thus by adapting the window frame at the time of making the same to receive the sashes and the attaching and locking mechanism, the attaching and locking mechanism can be added at any time.

Another object of this invention is to obviate the use, for securing the two sashes in the closed position in a single plane, of a bolt or cockspur or other fastening separately operated from the locking mechanism by which the window is securely held in any one of its range of positions, and this object is attained by providing a latch or other catch on the sashes, adapted, when the window is closed, to be operated directly or indirectly from the locking bar, when this is rotated to engage a part of the frame or the fitting, and so lock the sashes intermediate of the free ends thereof.

In order to secure the handle of the locking mechanism in the locking position, and to prevent possibility of water and wind blowing through the working slot for the handle working the locking mechanism, when the locking bar is located in the check bead and the operating handle or lever of the bar is directly connected thereto, the lever is passed through the check bead, a pivoted cover plate for the slot is provided having a notch, adapted when the cover plate is rotated to engage the handle when in the locking position.

The improvements set forth above are illustrated in the accompanying drawings as applied to a window in which the locking

mechanism is located at the bottom of the window.

In this drawing, Figure 1 is a vertical transverse section through the window, and 5 Fig. 2 a sectional plan thereof; Figs. 3, 4, 5 and 6 are detail views showing the locking bar and supporting brackets; Figs. 7 and 8 are further detail views showing the intermediate catch operated by the locking bar, 10 and Fig. 9 is a broken sectional plan through the top bar of the frame showing the guide.

Referring to the drawings the check bead 1 is formed as shown to provide a channel for the locking mechanism and is assembled 15 with the frame 2 to be fixed in the building. The top bar of the frame 2 is, during the course of construction of the frame, provided with a groove extending as shown in Fig. 9 beyond the inner faces of the side bars, 20 and adapted to receive a channel guide 3 the length of which is approximately equal to the width between the side bars of the frame. The channel guide 3 is preferably formed as shown with inturned side lips. Running in 25 the channel guide 3 are slides 4 which are grooved to receive the lips on the channel guide and provided with holes for the pivot pins 5. The top pivot pin 5 is arranged on a plate 6 which is screwed to the top of the 30 sash.

The pivot ends 7 of the locking bars 8 are carried by right-angled bracket plates 9 which are screwed to the check bead and frame.

35 In order to facilitate the insertion and removal of the bar 8 and to prevent side-play when inserted, one of the end brackets 9, see Fig. 5, is formed with a keyhole slot 10, and the corresponding trunnion 7 as shown to the 40 right hand of Fig. 3 is extended, and the extension provided with a corresponding lug or feather 11 which is so located that the bar 8 must be turned beyond its normal arc of oscillation to permit of the lug entering the 45 slot in the bracket 9. When this is done the bar can be moved a sufficient distance through the said key-hole-slotted end bracket to permit the opposite pivot end to be brought exactly opposite the hole in the 50 end bracket corresponding thereto. The bar is then drawn back to enter the last mentioned pivot end into the bracket and allowed to drop square, when the lug will then be at an angle to the slot and in conjunction 55 with the shoulder, at the other end will prevent any lateral movement of the bar.

To obviate the use, for securing the two sashes in the closed position in a single plane, of a bolt or cockspur or other fastening 60 separately operated from the locking mechanism by which the window is securely held in any one of its range of positions, a latch or other catch 12 is provided on the sashes, adapted, when the window is closed, 65 to be operated directly, as shown, or it may

be indirectly, from the locking bar 8, when this is rotated, to engage a part of the frame or the fitting, or as shown the plate 13, and so lock the sashes intermediate of the free ends thereof.

In order to prevent possibility of water and wind blowing through the working slot, 70 14, for the handle 15 working the locking mechanism, when the operating handle or lever of the bar is directly connected thereto, 75 the slot is provided with a pivoted cover plate 16. The plate 16, is provided with a notch 17, so that when the plate is moved over the slot, into the position shown in dotted line, the handle 15 will be held in the 80 locking position.

When the window sashes are opened to the full extent the adjacent ends of the slides 4 will, or may, come violently into contact, and to avoid straining the hinge joints of 85 the sashes under these circumstances, a corresponding stop is provided at the bottom of the sashes by arranging a tail piece 18, see Fig. 2, on each hinge plate 19 of sufficient length to make contact simultaneously 90 with the slides 4.

With the arrangements described the guiding and locking mechanism can be easily fitted to the frame at any time after the frame has been fixed in the building, without in any way interfering with or cutting the frame. It is obvious that the attaching and locking mechanism may, if desired, be arranged at the top of the window.

Having thus described my invention what 100 I claim and desire to secure by Letters Patent of the United States of America is:

1. In a window the combination of a frame, a plurality of sashes, each sash having one stile hinged to the adjacent stile of the 105 next succeeding sash and the opposite stile provided with a pivot at one end running in a corresponding groove in said frame, a second groove in a face of said frame at right angles with the face of said pivot groove, a 110 member hinged to said opposite stile adapted to travel in said second groove, means for holding all of said members in any desired positions within the limits of their movements, and a catch provided on the sashes, 115 adapted when these are in the closed position in a single plane, to be actuated by said holding means to engage a part of the frame.

2. In a window, the combination of a frame, a plurality of sashes, each sash having one stile hinged to the adjacent stile of the next succeeding sash and the stile opposite to the first-named stile being provided with a pivot at one end running in a corresponding groove in said frame, a 125 member hinged to said opposite stile of each sash, a guide common to all of said members, a recess cut in a face of the frame parallel to the face of the window and means located in said recess for securing all of said 130

members in any desired positions within the limits of their movements, and a catch provided on the sashes, adapted when these are in the closed position in a single plane to be 5 actuated by said holding means to engage said guide.

3. In a window the combination of a frame, a plurality of sashes, each sash having one stile hinged to the adjacent stile of 10 the next succeeding sash and the opposite stile provided with a pivot at one end running in a corresponding groove in said frame, a second groove in a face of said frame at right angles with the face of said 15 first groove, a member hinged to said opposite stile adapted to travel in said second groove, a bar eccentrically mounted in said second groove, means for turning said bar to secure all of said members in any desired 20 positions within the limits of their movements, and a catch provided on the sashes, adapted, when the window is closed, to be actuated by said eccentrically mounted bar, and engage a part of the frame.

25 4. In a window, the combination of a frame, a plurality of sashes, each sash having one stile hinged to the adjacent stile of the next succeeding sash, and the opposite stile provided with a pivot at one end, 30 a slide into which the pivot passes, a groove in the frame, a channel shaped guide arranged therein, in which the said slide runs, a member hinged to said opposite stile of each sash, a guide common to all of said 35 members, a recess cut in a face of the frame parallel to the face of the window, brackets fitted in said recess, a bar mounted eccentrically on trunnions in said brackets, one of said trunnions being extended, a lug on said extended trunnion, a corresponding slot in one of the brackets and means for rotating 40 said bar to secure all of said members in any desired positions within the limits of their movements.

45 5. In a window, the combination of a frame, a plurality of sashes, each sash having one stile hinged to the adjacent stile of

the next succeeding sash, and the opposite stile provided with a pivot at one end, a slide into which the pivot passes, a groove in 50 the frame, a channel shaped guide arranged therein, in which the said slide runs, a member hinged to said opposite stile of each sash, a tail piece on said member, a guide common to all of said members, a recess cut 55 in a face of the frame parallel to the face of the window, brackets fitted in said recess, a bar mounted eccentrically on trunnions in said brackets, one of said trunnions being extended, a lug on said extended trunnion, 60 a corresponding slot in one of the brackets, and means for rotating said bar to secure all of said members in any desired positions within the limits of their movements.

6. In a window, the combination of a 65 frame, a plurality of sashes, each sash having one stile hinged to the adjacent stile of the next succeeding sash, and the opposite stile provided with a pivot at one end, a slide into which the pivot passes, a groove 70 in the frame, a channel shaped guide arranged therein, in which the said slide runs, a member hinged to said opposite stile of each sash, a guide common to all of said members, a recess cut in a face of the frame 75 parallel to the face of the window, brackets fitted in said recess, a bar mounted eccentrically on trunnions in said brackets, one of said trunnions being extended, a lug on said extended trunnion, a corresponding 80 slot in one of the brackets, a handle for rotating said bar to secure all of said members in any desired positions within the limits of their movements, a slot in the frame through which said handle projects, a pivoted cover 85 plate for the slot, and a notch in said cover plate for engaging with said handle when in the locking position.

In testimony whereof I affix my signature in presence of two witnesses.

HERBERT JAMES MARTIN.
